(57) **CLAIM**

The ornamental design for a hanger support for a suitcase, as shown and described.

DESCRIPTION

FIG. 1 is a perspective view of a hanger support for a suitcase showing my new design;

FIG. 2 is a front elevational view thereof, the opposite end being identical in appearance;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof, the suitcase and the hanger depicted by means of broken lines being for illustrative purposes only and forming no part of the claimed design.
